UNITED STATES PATENT OFFICE.

STANLEY P. THOMAS, OF LOS BANOS, CALIFORNIA.

LIQUID-FUEL BURNER.

Application filed February 21, 1924. Serial No. 694,350.

To all whom it may concern:

Be it known that I, STANLEY P. THOMAS, a citizen of the United States, residing at Los Banos, in the county of Merced and State of California, have invented certain new and useful Improvements in Liquid-Fuel Burners, of which the following is a specification.

This invention relates to improvements in liquid fuel burners and has as its object to provide a liquid fuel burner which will be simple in construction, not liable to become clogged, and highly efficient in operation.

Another object of the invention is to provide, in a liquid fuel burner, a novel construction of generating chamber in which the liquid fuel may be completely vaporized before reaching the burner nozzle, thereby insuring of economy in the consumption of fuel.

The invention also has an object to provide, in a liquid fuel burner, a novel form of nozzle which will be interiorly of such contour as to permit of its being thoroughly cleaned if occasion should require.

In the accompanying drawings:

Figure 1 is a vertical sectional view through a liquid fuel burner constructed in accordance with the present invention;

Figure 2 is a top plan view of the burner;

Figure 3 is a horizontal sectional view taken substantially on the line 3—3 of Figure 1 looking in the direction indicated by the arrows.

The burner embodying the present invention comprises a generating chamber which is indicated in general by the numeral 1 and which embodies a base 2 adapted to be mounted within the fire box of a furnace, stove, or other heating apparatus, in any of the customary manners.

The generating chamber further includes an upstanding wall 3 which is preferably of cylindrical form as shown in Figure 3 of the drawings and which is integral with the said base. The upper portion of the wall 3 is inclined inwardly, as at 4, and is of substantially frusto-conical form, and integral with this portion of the wall 3 is the top of the generating chamber which is indicated by the numeral 5. The said top of the generating chamber is of concavo-convex form as best illustrated in Figure 1 so that its concave upper side constitutes a fuel pan which is indicated by the numeral 6.

Interiorly the generating chamber 1 is

formed with a partition wall 7 which extends chordally across the interior of the cylindrical casing and is integral with the bottom 2 and wall 3 thereof, the upper edge 60 of the said partition wall terminating relatively close to the under side of the pan 6. Preferably the wall 3 of the generating chamber 1, at diametrically opposite sides, is of increased thickness so that the inner surface of the wall at these two points is flat, these thickened portions being indicated one by the numeral 8 and the other by the numeral 9. The partition wall 7 is located in a vertical plane parallel to the face of the 65 thickened portion 8, and relatively close thereto. Formed integral with the partition wall 7 and with the bottom 2 of the generating chamber, is a baffle indicated in general by the numeral 10. The said baffle comprises 70 a top wall 11 which is flat and substantially horizontally disposed, arcuate side walls 12 which extend between the said top 11 and the bottom 2, and a front wall 13 which extends between the arcuate side walls 12 and 75 is located substantially in a plane parallel to the face of the thickened portion 9 of the wall of the chamber.

The walls 12 and 13 of the baffle are cast integral with the bottom 2 of the generating 80 chamber and are likewise integral with the top wall 11. The side walls 12 of the said baffle are concentric to and spaced inwardly from the relatively adjacent sides of the wall 3 of the chamber and are integral with 85 the said partition wall 7. By reference to Figure 1 of the drawings it will be observed that the top wall 11 of the baffle is located in a plane below the upper edge of the partition wall 7 and immediately below the top 90 5 of the generating chamber. The numeral 14 indicates a liquid fuel supply pipe which leads from any suitable source of supply by gravity or under pressure, and is threaded 95 into an opening 15 formed in the thickened 100 portion 9 of the wall 3, the discharge end of the pipe communicating with the interior of the generating chamber at a point directly opposite the wall 13 of the baffle 10.

The numeral 16 indicates a fuel conducting pipe which is of substantially U-shape and has one end threaded into an opening 17 formed in the thickened portion 8 of the wall of the generating chamber, the pipe curving upwardly and thence inwardly so 110 that its other end is positioned substantially above the pan 6.

The nozzle of the burner is indicated in general by the numeral 19 and the same comprises a hollow substantially spherical head 20 provided with a tubular extension 21 at 20 one side which is threaded or otherwise fitted to the upper end of the fuel conducting pipe 16. A perforation 22 is formed in the under side of the head 20 and is located preferably directly in vertical alinement with the center 10 of the pan 6.

In the operation of the burner, a small quantity of fuel is poured into the pan 6 and ignited, and the heat generated by the burning fuel will be absorbed by the pan and 15 the walls of the generating chamber so that when fuel is admitted to the chamber through the pipe 14, it will be vaporized and, sweeping over the baffle 10 and the upstanding partition or baffle wall 7, will, in the form 20 of gas, pass out through the pipe 16 and to the nozzle 19 and through the perforation 22 thereof, the fuel being ignited and the flames being delivered in the direction of the pan 6. It will be evident that as the burner continues 25 in operation, the walls of the generating chamber as well as the walls of the baffle 10, will become highly heated so that the fuel will be vaporized substantially at the instant it enters the generating chamber, 30 the generated gases being likewise subjected to an elevated temperature so that they are in a highly heated state when they issue through the aperture 22. It will likewise be evident that the pan serves not only to contain 35 the quantity of fuel necessary to start the burner, but, in the operation of the burner, it constitutes a flame spreader, so that the flames from the burning fuel are spread in all directions from the burner. 40 It will be observed that the walls 7, 11, 12 and 13 constituting the baffle 10 are of substantially uniform thickness and that they enclose a space 10' in the lower portion of the burner, an opening 11' being formed 45 through the base 2 of the burner and communicating with the said base. This construction is of advantage inasmuch as due to the free circulation of air which may take place in the space 10' and likewise due to the 50 substantially uniform thickness of the walls of the baffle, expansion and contraction will take place uniformly and likewise the baffle walls will be more readily heated to the required degree of temperature than if the 55 baffle were formed solid throughout.

Having thus described the invention, what is claimed as new is:

1. A liquid fuel burner comprising a generating chamber having a top, the upper 60 side of which is curvilinearly concave, to provide a pan to initially receive fuel and to serve later as a flame spreader, an upstanding baffle within the said chamber, means for supplying liquid fuel to the chamber at one side of the baffle, means for con-

ducting gaseous fuel from the chamber at the opposite side of the baffle, and a nozzle in communication with the said conducting means and having a discharge orifice presented toward the said top of the chamber. 70

2. A liquid fuel burner comprising a generating chamber having a top, the upper side of which is curvilinearly concave, an upstanding baffle within the chamber, means for supplying liquid fuel to the said chamber at one side of the baffle, a pipe in communication with the chamber at the other side of the baffle for conducting gaseous fuel from the chamber, the said pipe extending upwardly and thence inwardly to a 80 point above the chamber, and a nozzle supported upon the upper end of the pipe, the nozzle being provided in its under side with an orifice and the said under side of the nozzle being presented toward the concave 85 top of the chamber.

3. A liquid fuel burner comprising a generating chamber having a top, a hollow baffle within the chamber upon the bottom thereof having a wall presented toward one 90 side of the chamber, a partition wall constituting likewise a baffle and closing one side of the said hollow baffle and presented toward the opposite side of the wall of the chamber, means for introducing liquid fuel into the said chamber through the first mentioned side of the wall thereof and against the hollow baffle, means for conducting gaseous fuel from the chamber at the other side of the wall thereof and at a point opposite the said partition wall, and a nozzle supplied with gaseous fuel from the said conducting means and having a discharge orifice presented toward the said top of the said chamber. 100

4. A liquid fuel burner comprising a generating chamber having a top, a hollow baffle within the chamber upon the bottom thereof and having a wall presented toward one side of the chamber, a partition wall 110 constituting likewise a baffle and closing one side of the said hollow baffle and presented toward the opposite side of the wall of the chamber, means for introducing liquid fuel into the said chamber through the first 115 mentioned side of the wall thereof and against the hollow baffle, means for conducting gaseous fuel from the chamber at the other side of the wall thereof and at a point opposite the said partition wall, and a nozzle supplied with gaseous fuel from the said conducting means and having a discharge orifice presented toward the said top of the said chamber, the said partition wall having its upper portion extending above 125 the top of the baffle and terminating short of the under side of the top of the chamber.

5. A liquid fuel burner comprising a generating chamber having a top, the upper side of which is curvilinearly concave, the 130

said chamber likewise having a bottom and a surrounding circumferential wall, an up-standing baffle wall within the chamber extending from the bottom thereof to a point spaced below the said top of the chamber, a fuel outlet conducting pipe extending from the chamber and communicating therewith at a point opposite said wall, a nozzle at the other end of the said conducting pipe having a discharge orifice presented toward the upper side of the said top of the chamber, and a hollow baffle comprising a top wall and a circumferential wall, the circumferential wall upstanding from the bottom of the said chamber and the top wall of the baffle and the end of the

circumferential wall thereof meeting the face of the first mentioned baffle wall, the first mentioned baffle wall having its upper portion extending above the plane of the top ²⁰ wall of the hollow baffle, the said hollow baffle being exteriorly of a diameter less than the internal diameter of the chamber whereby its outer side will be spaced therefrom throughout its circumference, and a ²⁵ fuel inlet pipe opening into the said chamber at a point opposite the intermediate portion of the circumferential wall of the hollow baffle.

In testimony whereof I affix my signature.

STANLEY P. THOMAS. [L.S.]
